RAILWAY CAR TRUCK

Karl F. Nystrom and Vernon L. Green,
Milwaukee, Wis.

Application October 6, 1941, Serial No. 413,850

5 Claims. (Cl. 105—197)

Our invention relates more particularly to trucks for railway freight cars and involves a main or outer frame or wheel piece provided with integral journal boxes and having side openings and an inner or sub-frame yieldably supported on the main frame by triple coil springs and held in lateral and longitudinal alignment with the outer frame through the medium of a removable shoe which permits removal of the wheel piece when wheel change becomes necessary without disturbing any portion of the truck except the shoes and wheel piece.

The invention also contemplates a construction wherein the brake rigging is carried by the sub-frame thus providing a spring borne brake rigging which is less subject to wear and failure.

Our improved truck also involves a truck bolster which is permitted lateral motion through the medium of shock absorbing resilient means whereby the bolster is supported on the sub-frame; the resilient means consisting of a rubber "sandwich" which is removably secured in place by interengaging surfaces on the upper element of the "sandwich" and the truck bolster and on the bottom element of the "sandwich" and the spring plank which is secured to the sub-frame.

The invention has for its object the provision of a truck which permits the use of coil springs with high deflection and wherein a shear deflection between the sub-frame and the bolster is provided through the rubber "sandwich," whereby the riding quality of the car is greatly improved.

The objects and advantages inherent in the construction all will be readily comprehended from the detailed description of the accompanying drawings wherein:

Figure 1 is a plan view of one side of our improved truck with portions broken away and shown in section.

Figure 2 is a longitudinal sectional view taken on the offset line 2—2 of Figure 1, looking in the direction of the arrows.

Figure 3 is a vertical sectional view taken on the line 3—3 of Figure 2 looking in the direction of the arrows.

Figure 4 is a detail perspective view of the bolster supporting resilient means.

In the particular exemplification of the invention, the main frame or wheel piece 10, consisting of the top and bottom rails 11 and 12 and vertically disposed columns 13, is provided at its ends with journal boxes 14 and with spring seats 15 adjacent the journal box portions of the frame.

5 Mounted within the main frame or wheel piece 10 is a sub-frame 16 provided adjacent its top with extended ends 17 and at its intermediate portion with a bolster receiving opening.

10 The ends 17 of the sub-frame are each provided with a shoe 18, see Figures 1 and 2. The main portion of the shoe is shown in the nature of a flat plate (see Figure 2) which is provided with a plurality of upstanding studs or pins 19 which extend into holes formed in the bottom surface of the extended ends of the sub-frame, thereby removably connecting the shoes to the sub-frame. The outer ends of the shoes are vertically enlarged coextensive with the thickness of the sub-frame ends as shown at 20, Figure 2, and the outer vertical face of the enlarged portion of each shoe formed to extend into a vertically disposed socket as at 21 formed in the adjacent portion of the wheel piece 10 and permits relative vertical movement between the sub-frame and wheel piece or main frame 10; the interengaging relation between the shoes and the wheel piece maintaining the sub-frame in lateral and longitudinal alignment with the wheel piece. In order to compensate for wear the contacting surfaces of the shoes and the wheel piece sockets or pockets are preferably provided with steel liners as shown at 22, see Figure 1.

15 As is apparent from the construction, the connection between the sub-frame 16 and the wheel piece or outer frame 10 may be readily disrupted or released by disengaging the shoes from the vertical slideways or sockets in the outer frame; the arrangement permitting wheel changes to 20 be made without disturbing any portion of the truck except the shoes 18 and the wheel piece or outer frame 10, as the brake rigging and bolster supporting means (later described) are entirely carried by the sub-frame 16; the brake 25 hangers being mounted on the extensions or brackets 23 formed on the sub-frame. With this arrangement the brake rigging is spring borne and therefore less subject to wear and failure.

20 The lower faces of the shoes 18 are formed to provide proper seats for the triple coil springs 24 which also seat on the spring seats 15 formed in the wheel piece or outer frame 10.

25 The construction of the wheel piece and of the sub-frame permits the coil springs to be placed close to the truck axles and also enables the use of triple coil springs with a high deflection which greatly improves the riding quality of the car; for example, springs with a three and a half inch total deflection, as compared with about one and five-eighths inches employed with the

present standard freight car springs, may be used.

The lower beams of the sub-frames 16 at the window-openings therein provide support for the ends of the spring plank 25. The ends of the plank 25 are provided with openings to receive the upstanding ribs 26 formed on the lower rail of the sub-frame 16 and the metal of the spring plank 25 adjacent the openings is depressed to engage the ribs 26 as shown at 27 and provide a non-shifting connection between the spring plank and the sub-frame.

The truck bolster 28 is provided with reduced end portions 29 which extend into the window-openings of the sub-frame and are supported on the bottom rail of the sub-frame through the medium of a rubber "sandwich" composed of comparatively thick rubber pads 30, 30 which are bonded to the steel plates 31, 31, 31; the "sandwich" preferably being substantially coextensive with the width of the bolster ends as shown in Figure 2. The "sandwich" at each side of the truck is operatively or non-shiftably connected to the ends of the bolster 28 and to the spring plank 25 by means of studs or lugs 32 welded or integrally secured to the top and bottom plates 31; the lugs 32 of the top plate engaging in holes or notches formed in the bottom surface of the ends of the truck bolster 28 while the lugs 32 on the bottom plate 31 enter holes formed at the ends of the spring plank 25; the latter being non-shiftably secured to the sub-frame as heretofore described. The construction described permits the truck bolster to have lateral motion through the shear deflection of the rubber "sandwiches" which absorb the vibrations of the sub-frame and of the truck bolster.

In order to limit the degree of lateral motion of the bolster, the ends of the latter are shown provided with the spaced lugs 33 arranged on each side of the bolster; the lugs on the same side of the bolster being spaced apart a predetermined distance greater than the width of the sub-frame through which the end of the bolster extends.

The lugs 33, as shown in Figure 1, will contact the columns 16^a of the sub-frame in the event of excessive movement of the bolster transversely of the truck.

The depth of the pins or studs 32 of the "sandwiches" is such that the pins will clear the openings or notches in the spring plank 25 or in the bottom of the bolster when the latter is jacked up thus enabling assembly and dissociation to be easily accomplished.

The exemplification of the invention is believed to be the best embodiment thereof, but certain structural modifications are possible and may be made without, however, departing from the spirit of our invention as defined in the appended claims.

What we claim is:

1. A railway car truck comprising an outer frame composed of top and bottom rails terminating at their ends in integral journal boxes having open-ended vertical slots in their side walls, the bottom rail being provided with spring seats adjacent the journal boxes; a sub-frame composed of top and bottom rails united adjacent the top of the frame in horizontally disposed ends, said sub-frame being arranged with in the outer frame in spaced relation with the top and the bottom rails thereof and with its ends disposed above the spring seats; members removably secured to the ends of the sub-frame

and extending into said vertical slots whereby alignment between the two frames is maintained and relative vertical movement between the outer frame and the sub-frame is permitted while movement of said members out of said slots permits removal of the outer frame; and high deflection springs between said spring seats and said removable members.

2. A railway car truck comprising a pair of outer frames and a pair of sub-frames; the outer frames being provided at the ends with integral journal boxes and spring seats adjacent the journal boxes, the outer frames adjacent the journal boxes being provided with vertically extending open-ended recesses; the sub-frames being arranged within the outer frames and provided with ends extending above the spring seats; removable shoes having pin-and-socket connection with the lower faces of the sub-frame ends and adapted to extend into said recesses for maintaining alignment between the outer and the sub-frames; high deflection springs mounted between the spring seats and said shoes; and a spring plank for anchoring the two sub-frames together, the ends of the spring plank having vertically releasable interengagement with the sub-frames.

3. A railway car truck comprising a pair of outer frames and a pair of sub-frames yieldingly mounted within the outer frames, all of the frames being provided with window-openings; removable means in supporting relation with the ends of the sub-frames and in interengaging relation with the outer frames whereby the frames are maintained in lateral and longitudinal alignment and dissociation of the outer frames and the sub-frames permitted; a spring plank whose ends have interlocking engagement with the sub-frames at opposite sides of the truck; a rubber cushion element arranged on each end of the spring plank within the window-openings of the sub-frames; and a truck bolster whose ends are seated on said cushion elements.

4. In a railway car truck, outer frames composed of top rails and bottom rails united at the ends in journal box forming portions and having window-openings, the side walls of said journal box portions being provided with open ended vertical slots while the bottom rail adjacent the journal box portions is provided with spring-seats; sub-frames each composed of top and bottom beams united adjacent the top in longitudinally disposed flat-faced ends, the sub-frames being arranged within the outer frames and provided with brake hanger brackets and with window-openings; shoes removably engaged with the ends of the sub-frames and arranged to slide vertically in said vertical slots to maintain alignment between the outer frames and the sub-frames; coil springs arranged on said spring seats in supporting relation with said shoes; a spring plank disposed transversely of the truck for linking the sub-frames at opposite sides of the truck together, the ends of the plank having lug-and-socket relation with the bottom rails of the sub-frames; a rubber cushion element arranged on each end of the spring plank; and a truck bolster whose ends extend into said window-openings and seat on said cushion elements whereby lateral movement between the bolster and the sub-frames is permitted through shear deflection of the cushion elements.

5. A railway car truck comprising a pair of outer frames or wheel pieces and a pair of bolster carrying sub-frames arranged within the

wheel pieces, the wheel pieces and the sub-frames being composed of top and bottom rails united adjacent the ends, the wheel pieces at their ends being provided with integral journal boxes, vertically extending recesses adjacent the upper rails and spring seats on the bottom rails adjacent the journal boxes, the sub-frames being arranged between the top and bottom rails of the wheel pieces and provided at the top with longitudinally disposed ends disposed above the spring seats on the bottom rails of the wheel pieces and terminating a distance removed from said recesses; removable shoes arranged on the bottom of said

sub-frame ends with slot and pin engagement therewith while the ends of the shoes extend vertically at the ends of the sub-frames and slidably engage in said recesses and thereby effect interengaging relation between the sub-frames and the wheel pieces; and high deflection springs mounted on said spring seats in bearing relation with the bottoms of said shoes for yieldingly supporting the sub-frames and maintaining said shoes in place.
